UNITED STATES PATENT OFFICE

HAROLD EDWARD JOSCELYN CAMPS, OF LONDON, ENGLAND

HULL STRUCTURE OF SHIPS AND THE LIKE

Application filed August 21, 1929, Serial No. 387,324, and in Great Britain August 28, 1928.

This invention relates to improvements in hull structures of ships and the like and has for one of its objects to produce a hull structure of greater strength than that of known 5 hull structures of similar weight.

A further object of the invention is to produce a hull structure having a greater dead weight carrying capacity than has been possible with known constructions.

10 Another object of this invention is the abolition of all vertically arranged frames connected to the plating of the side walls and the substitution therefor of diagonally arranged frames thereby enabling greater 15 strength on a weight for weight basis to be obtained than has been possible heretofore.

Other objects of the invention are to reduce the cost of construction and also reduce the possible source of leakage through the skin 20 of the ship.

In the past it has been customary to construct hulls with vertical or longitudinal frames to which the side walls are attached and it has been proposed to brace the vertical 25 frames in such constructions by diagonally arranged members said members in some instances being attached to the skin of the vessel.

The invention consists in the attachment 30 of the plating of each side wall of the hull to a plurality of substantially parallel obliquely arranged frames which do not intersect with one another and which are connected to longitudinal girders at the upper 35 and lower parts of the hull, the said longitudinal girders in some cases being supplemented by additional girders intermediately arranged.

In the drawings:—

40 Figure 1 is a side elevation of one form of vessel constructed in accordance with this invention;

Figure 2 is a plan view thereof;

45 Figure 3 is a cross sectional elevation showing a suitable position for the longitudinal girders;

50 Figure 4 is a fragmentary perspective view illustrating one way of arranging flat bulk heads without the cutting or interrupting of the diagonal frames;

Figure 5 is a fragmentary perspective view illustrating an alternative way of arranging flat bulk heads and in which the members forming the diagonal frames although interrupted are so connected with the bulk head 55 that the strength of the construction is maintained;

Figure 6 is a fragmentary perspective view illustrating one way of arranging corrugated bulk heads without the cutting or interrupting 60 of the diagonal frames; and

Figure 7 is a fragmentary perspective view illustrating an alternative way of arranging corrugated bulk heads and in which the members forming the diagonal frames although 65 interrupted are so connected with the bulk head that the strength of the construction is maintained.

In the form of construction illustrated in the drawings each side wall has three longitudinal girders *a* which are of box or trunk form extending substantially from one end of the vessel to the other, see Figure 2. The longitudinal girders *a* to be associated with a side wall are connected together by frames *b* which are diagonally arranged. The frames *b* may be in the form of a bulb angle 70 or other cross section suitable for attachment to the girders *a* and for the attachment thereto of the side plating *c*.

The side plating *c* is connected to the diagonal frames *b* in any ordinary manner, for example by riveting and the structure as a whole may be provided as illustrated with a keel *d* and double bottom tanks *e*.

To avoid difficulties at the extreme ends of the hull structure it will be noted that the diagonal frames and the longitudinal girders do not extend beyond a certain point, the fore peak and after peak being of ordinary construction.

To introduce the requisite transverse strength bulk heads *g* are provided, said bulk heads *g* being of ordinary flat form see Figures 4 and 5, or of corrugated form see Figures 6 and 7, as desired.

The arrangements illustrated in Figures 4 and 6 enable the continuity of the frames *b* to be maintained, the bulk head *g* being suitably notched and supported by shoes such 100

as *f* whilst the arrangements illustrated in Figures 5 and 7 enable cost to be reduced, the frames *b* being cut to avoid the bulk head *g* to which said frames *b* are attached by 5 brackets such as *h*.

For clarity of illustration the means for connecting the parts together such as rivets or the like are omitted and it will be understood that the introduction of such means is 10 within the knowledge of those skilled in hull design and construction.

When the bulk heads *g* are formed with vertically arranged corrugations then a short section with horizontally arranged corrugations 15 is mounted on the side plating as illustrated in Figures 6 and 7 said short section having a vertically arranged web plate *k* (Figure 1) on the edge remote to the hull and to which the bulk head with vertically arranged corrugations is connected in well 20 known manner.

It will be seen that owing to the arrangement of the frames *b* in a diagonal direction not only is resistance afforded to local def- 25 formation of the hull plating in the event of impact with horizontal or vertical obstructions but the material in said members is ar- ranged in a more economical manner thus en- abling a hull to be produced of a given size 30 and strength which is lighter in weight than that obtained by known constructions.

The longitudinal girders *a* when formed hollow, as illustrated in the drawings, en- 35 able more adequate ventilation of the com- partments of the hold to be obtained than has been possible hitherto certain of the girders *a* being adapted to be employed for the de- livery of air to the compartments whilst other of the girders are adapted to collect air 40 discharged from the compartments and de- liver it externally.

It will be understood that the longitudinal girders *a* and diagonal frames *b* may be of any shape or cross section as may be found 45 most satisfactory or convenient in use, the girders *a* when of box form being either oblong, square, triangular or polygonal or with one or more rounded sides in transverse section as may be most convenient.

50 As illustrated in Figure 3 the longitudinal girder *a* at the turn of the bilge is substantially triangular in cross section whilst the remainder of the girders *a* are polygonal in form.

55 Although for the purposes of illustration all the diagonal member *b* have been shown as inclined in the same direction obviously if desirable or necessary the said diagonal members between any pair of bulk heads may 60 be inclined in opposite direction to the members between another pair of bulk heads.

I claim:-

1. A main hull structure for ships and the like comprising only in combination a plurality of substantially parallel obliquely

and uni-directionally arranged frames be- 70 tween the bulkheads, longitudinal girders at the upper part of the hull to which the frames are connected, longitudinal girders at the lower part of the hull to which the frames are connected and plating attached to the frames and the girders so as to form the side walls of the hull.

2. A main hull structure for ships and the like comprising only in combination a plu- 75 rality of substantially parallel obliquely and uni-directionally arranged frames between the bulkheads, a plurality of longitudinal girders connected to said frames, one of said girders being arranged at the upper part of the hull and one of the said girders being ar- ranged at the lower part of the hull and plating attached to the frames and girders so as to form the side walls of the hull.

3. A main hull structure for ships and the like comprising only in combination a plu- 80 rality of substantially parallel obliquely and uni-directionally arranged frames between the bulkheads, a plurality of longitudinal girders connected to said frames, one of said girders being arranged at the upper part of the hull and one of the said girders being ar- ranged at the lower part of the hull and plating attached to the frames and girders so as to form the side walls of the hull, some or 85 all of the longitudinal girders being of box form.
